WOOD PLANE AND DRAWKNIFE

Edwin G. Simon, San Francisco, Calif.

Application April 11, 1947, Serial No. 740,900

5 Claims. (Cl. 30—281)

1

The present invention relates to a plane, and more particularly to a plane or drawknife type of device adapted for use by model makers and in similar types of work.

An object of the present invention is to provide a plane for use by model makers, violin makers, and others engaging in precise wood-work, which may be pushed with one hand by the operator or which may be pulled towards the operator similarly to spoke shave and drawknife work.

Another object of the present invention is to provide a combination plane and drawknife adapted for use on both concave and convex surfaces, and for planing operations across or against the grain of the wood being worked, and which may be guided by one hand of the operator for light or heavy cuts and in conformity with curved surfaces without permitting the plane iron to dig into the wood.

Again an object of the present invention is to provide a plane serving as both a block plane and drawknife which is adapted to be made of a minimum number of parts and with the parts so constructed in materials of dissimilar weights as to concentrate when in use the weight adjacent the plane iron and balance the plane along its cutting edge.

Yet another object of the present invention is to provide a plane which may be operated by one hand of the operator, with the heel of the hand propelling the plane with the fingers free to guide the plane horizontally to the left or right and to control, in conjunction with the pressure exerted by the heel of the hand, the vertical positioning of the plane iron in conformity with the shape of any surface being worked.

Still another object of the present invention is to provide a combination plane in which the plane handle serves as both the blade support and plane iron frog, and in which the plane handle is positioned to provide substantially a straight line of force between the portion of the handle pushed by the operator and the cutting edge of the plane iron.

Again another object of the present invention is to provide a plane in which the cutting edge of the plane iron is normally held away from the work when the plane is at rest, preventing injury to the work and to the plane iron.

The invention possesses other objects and features of advantage, some of which, with the foregoing, will be set forth in the following description of the preferred form of the invention which is illustrated in the drawings accompanying and

forming part of the specification. It is to be understood, however, that variations in the showing made by the said drawings and description may be adopted within the scope of the invention as set forth in the claims.

A description of the views:

Figure 1 is a perspective view of the combination plane or drawknife embodying the features of the present invention.

Figure 2 is a side elevation partially in cross section.

Figure 3 is a side elevational view of the plane.

The plane embodying the features of the present invention comprises, briefly, a plane body 15 having arms 6 and 7 extending transversely therefrom; a plane iron 8 having a cutting edge 9 variably positioned within the plane body 4, and a combination handle and plane iron cap 10 resting upon iron 8 and fixed to the body by means of a set screw 11.

Heretofore, while engaged in precise wood work as in violin making and scale model making, and especially where concave and convex surfaces are encountered, there has been available no adequate tool for smoothing and conforming variably curved wood surfaces. The wood worker relied on a variety of tools, a block plane for relatively flat surfaces; a "bullnose" plane for working close to corners and perpendicular edges, and for curved surfaces, spoke shaves, drawknives and gouges were used, but with these latter tools the depth of cut cannot be maintained uniformly nor controlled as with a plane. The combination plane or drawknife embodying the present invention is utilized for planing substantially flat surfaces, and for finishing both convex and concave curved surfaces, as well as for following irregular patterns and working across and against the grain of woods.

The plane body 4 is provided with a relieved portion 12 having an inclined rear base 13 upon which the plane iron is designed to seat and which establishes the proper cutting angle of the plane iron or cutter bit relative to the work. The plane iron 8 fits snugly against parallel transverse sides 14 and 15 of portion 12, with the cutting edge 9 of the iron projecting through a slot 16 provided in the bottom 17 in registration with the recess 12 of the plane body. As a means of holding the plane iron within the body, the handle 10 overlies the iron and the handle and iron are secured to the body by means of the aforesaid screw 11, which is preferably formed with a knurled head 18 for ready adjustment by the op-

erator. A slot 8 extending longitudinally of the plane iron 8 registers with the shank of screw 11 and permits longitudinal movement of the plane iron to vary the extent to which the cutting edge 9 protrudes below the bottom 17 of the body.

Handle 10 desirably overlies the plane iron for substantially its entire length, lending strength and rigidity thereto, and for this purpose the handle is formed with a substantially flat portion 19 approximately equal to the length of the plane iron 8. The handle 10 terminates rearwardly in an upwardly curved concave boss or offset 20 having a shank 21 positioned at an angle to the portion 19 of the handle. The boss 20 affords a conveniently shaped hand-engaging portion for nesting within the palm of the hand, and desirably the workman places the handle boss within the palm and extends his fingers forward along the handle and the plane body for guiding the progress of the plane as it is pushed by pressure exerted from the heel of the hand. It will be noted that the hand engaging portion of the handle is so positioned relative to the cutting edge of the plane iron 8 that a force exerted by the workman on the handle is transmitted in substantially a straight line relation to the cutting edge 9 of the cutter iron. The one-piece handle construction and the reinforcement of the plane iron afforded by the handle portion 19 combine with the straightline relation of handle to cutter tip to provide a highly controllable cutting instrument. By a slight wrist motion the workman is able to direct the plane upwardly or downwardly to conform to convex or concave surfaces, and a slight sidewise movement of the wrist enables the plane to follow a twisting horizontal course conforming to a pattern or a grain in the wood.

It is advantageous in performing some surfacing operations, particularly the planing of small cylindrical or tapered members and finishing of dished or concave surfaces to use a cutting tool employing a pulling rather than a pushing movement so that the workman may observe the cutting blade as it proceeds against the work and more accurately guide and control the extent of cutting. Accordingly, and as an important feature of the present invention, the plane body 4 has provided thereon the pair of arms 6 and 7 and as best shown in Figures 1 and 3 the arms incline upwardly from the body and are curved slightly to terminate in rounded tip 22 and 23 respectively. Arms 6 and 7 permit the pulling of the plane toward the operator, and additionally serve when the plane is being pushed by means of the handle in the usual manner as convenient leverage points for the fingers of the workman to more easily and accurately guide the horizontal movement of the plane.

The bottom 17 of the plane body is preferably convexly curved, tapering upwardly from adjacent the slot 16 to the edges of the body. This tapering permits a rocking of the plane about the fulcrum of the cutting edge and a more ready conformity to curved surfaces. Depending upon the degree of curvature formed in the bottom 17, and in the type of material in the plane iron 8, the plane may be used on substantially straight or curved surfaces, or exclusively upon wood or upon the softer metals. The body 4 and arms 6 and 7 are desirably constructed of a relatively durable and hard material, such as brass, while it is desirable to form the handle of a lighter material, such as a plastic or an aluminum alloy, thereby maintaining the desirable concentration of weight adjacent the cutting edge of the

tool. However, and as an important feature of the present invention, the length of the rearward extension of the handle and the leverage exerted thereby is sufficient to cause the plane, when unsupported by the hand, and as shown in Figure 3, to rock about the rear edge 24 of the bottom 17, lifting the base 12 of the plane out of contact with the work and protecting both the work and the cutting edge of the plane iron from injurious contact.

I claim:

1. A woodworking tool comprising, a base member having a work-engaging surface convex on the bottom and formed with a rectangular recess in the upper side thereof communicating with said surface in an elongated slot extending widthwise of the member, the bottom of said recess being inclined forwardly to said slot with the plane of said bottom intersecting said slot, a flat rectangular cutter blade mounted upon said recess bottom and having a forwardly arranged sharpened end thereof positioned through said slot at said work-engaging surface, the sharpened end of said blade being convexly curved in general conformance with the curvature of said surface, a handle having a flat rectangular portion mounted in said recess directly upon said blade to support the latter between said portion and said recess bottom and having an upwardly and rearwardly offset portion formed for engagement in the palm of the hand of the user for forward displacement of said work-engaging surface over the work, and fastening means removably securing said blade and handle in connected position to said base member and said blade having a slot cooperating with said fastening means to permit adjustment thereof into and from said slot.

2. A woodworking tool comprising, a base member having a work-engaging surface convex on the bottom and formed with a rectangular recess in the upper side thereof communicating with said surface in an elongated slot extending widthwise of the member, the bottom of said recess being inclined downwardly and forwardly to said slot with the plane of said bottom intersecting said slot, a flat rectangular cutter blade mounted upon said recess bottom and having a forwardly arranged sharpened end thereof positioned through said slot at said work-engaging surface, the sharpened end of said blade being convexly curved in general conformance with the curvature of said surface, a handle having a flat rectangular portion mounted in said recess directly upon said blade to support the latter between said portion and said recess bottom and having an elevated and rearwardly offset end portion formed for engagement in the palm of the hand of the user for forward displacement of the tool over the work, fastening means removably securing said blade and handle in connected position to said base member, and a pair of arms positioned on said base member extending outwardly therefrom substantially parallel to said slot and having the outer ends thereof positioned for engagement by the fingers of the hand for guiding said displacement.

3. A woodworking tool comprising, a base member having a work-engaging surface convex on the bottom and formed with a rectangular recess in the upper side thereof communicating with said surface in an elongated slot extending widthwise of the member, the bottom of said recess being inclined downwardly and forwardly to said slot with the plane of said bottom intersecting said slot, a flat rectangular cutter blade mount-

ed upon said recess bottom and having a forwardly arranged sharpened end thereof positioned through said slot at said work-engaging surface, the sharpened end of said blade being convexly curved in general conformance with the curvature of said surface, a handle having a flat rectangular portion mounted in said recess directly upon said blade to support the latter between said portion and said recess bottom, a substantially convex hand-engaging terminus of said handle at the free end thereof and substantially parallel with said work engaging surface and being formed for engagement in the palm of the hand of the user for forward displacement of said tool over the work, and a pair of arms positioned on said member extending outwardly therefrom substantially parallel to said slot and positioned for engagement by the fingers of the hand in guiding said displacement.

4. In a tool of the character described, a body having a bottom work-engaging surface, a cutter blade carried by said body in a forwardly and downwardly inclined plane and having a sharpened forward edge at said surface, a pair of arms secured to said body and extending transversely from the opposite sides thereof generally parallel to the forward edge of said blade, and a handle secured to said body and extending rearwardly and upwardly therefrom and terminating in a rearwardly and substantially horizontally extending portion formed for engagement in the palm of the hand of the user for forward displacement of said tool over the work and with the fingers of the hand free to engage said arms for guiding said displacement.

5. In a tool of the character described, a body having a bottom work-engaging surface, a cutter

blade of flat form carried by said body in a forwardly and downwardly inclined plane and having a sharpened forward edge at said surface, a pair of arms secured to said body and extending transversely from the opposite sides of said body in an outwardly and upwardly inclined relation, a handle having a flat section mounted upon and supporting said blade over substantially the full length thereof, said handle having an adjoining section extending upwardly from the rearward end of said first section and terminating in a third section extending generally horizontally and rearwardly from said second section, said third section being formed for engagement in the palm of the hand of the user for displacement of said work-engaging surface in a forward direction over the work, and said arms being positioned for engagement by the fingers of the hand for guiding such displacement.
